(57) CLAIM

The ornamental design for a contoured jug, as shown and described.

DESCRIPTION

FIG. 1 is a perspective view of a contoured jug incorporating my new design;

FIG. 2 is a side elevational view thereof, the other side elevational view being a mirror image of that shown;

FIG. 3 is a top plan view thereof;

FIG. 4 is a rear elevational view thereof;

FIG. 5 is a front elevational view thereof; and,

FIG. 6 is a bottom plan view thereof.

The broken line is for illustrative purposes only and forms no part of the claimed design.
